UNITED STATES PATENT OFFICE.

RUBEN C. M. HASTINGS AND THURSTON MATHENY, OF ATHENS, OHIO.

LOCK-OUT DEVICE FOR TELEPHONES.

No. 821,800.

Specification of Letters Patent.

Patented May 29, 1906.

Application filed April 4, 1905. Serial No. 253,846.

To all whom it may concern:

Be it known that we, RUBEN C. M. HASTINGS and THURSTON MATHENY, citizens of the United States, residing at Athens, in the county of Athens and State of Ohio, have invented a new and useful Lock-Out Device for Telephones, of which the following is a specification.

This invention relates to telephone selecting and lock-out devices.

One object of the invention is to provide mechanism for use on party-lines by which it will be impossible for any subscriber to overhear a conversation between two connected subscribers on the same line and to place such mechanism under the control of the calling subscriber.

A further object of the invention is to provide a novel form of selecting means whereby any subscriber along the line may unlock the receiver-hook of any other subscriber in order to open communication with the latter while the hooks of all of the other subscribers on the line remain locked.

A still further object of the invention is to provide a circuit-breaking device that is in part controlled by the receiver-hook lock, so that said circuit-breaker can only be moved by a person whose receiver has been previously removed from the receiver-hook, and the line cannot be tampered with by other persons.

A still further object of the invention is to improve, simplify, and cheapen selectors of this character and to provide mechanisms which may be applied to existing telephone-lines without material change in the connections.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a diagram illustrating two stations on a

party-line provided with selecting and lock-out mechanism arranged and constructed in accordance with the invention. Fig. 2 is a detail elevation of the mechanism at a substation, showing the parts during a selecting movement. Fig. 3 is a similar view showing the position of the parts at the station of a called subscriber after the completion of a selecting movement. Fig. 4 is a sectional plan view of one of the switch-boxes at a substation. Fig. 5 is a detail perspective view of a portion of a switch-box. Fig. 6 is a detail view of the switch for breaking the selecting-circuit. Fig. 7 is a detail view of a modified form of circuit-closing means.

Similar characters of reference are employed to indicate corresponding parts throughout the several figures of the drawings.

The main-line wires 10 and 11 form the ordinary lines of a bridging-bell party-line system, and at each subscriber's station is a battery B, a transmitter T, a receiver R, a call-bell C, and a magneto-generator M. Each station is also provided with a receiver-hook H of the usual type, and the connections illustrated are conventional with the exception of the connection between the receiver-hook and the line-wire 11, this connecting-wire 12 being in the present instance interrupted by contacts 14 and 15, the latter being in the form of a movable arm normally so disposed that the talking-circuit and calling-circuit of every telephone is connected to the main line. In addition to these two line-wires, one or other of which may be in the form of a ground-return, a selecting-wire 16 is employed, this wire extending from station to station and being connected in series with selecting mechanism at each one of the subscriber's stations, the circuit being completed by the line-wire 11 or ground, so that when the line is energized the selecting devices of each station will be operated, the selecting movement being the same at each station and continuing until the mechanism at the station to be called has arrived at the proper point. The mechanism, as illustrated in Fig. 1, includes an electromagnet 17, having a serial connection with the wire 16, this line including two contacts 18 and 19, normally connected with each other. The ener-

gizing device is the battery B, which is connected by a wire 21 to a switch-point 22, which may be connected by a switch 23 to a local wire 24, leading to the selecting-wire 16. 5 The switch normally rests in contact with a switch-point 25, connected by a wire 26 to the battery, so that the battery is normally disconnected and the circuit of the selecting-wire completed by wire 24, switch 23, contact 25, and wire 16; but by moving the switch at any one station to the contact 22 the battery will be connected in the circuit, and all of the electromagnets 17 on the line will be energized, the person at the calling-15 station closing the circuit a number of times corresponding to the number of the station to be called.

At a point adjacent to the receiver-hook of each station is a pivot-stud 30, on which is mounted a receiver-hook-locking yoke 31, arranged to receive the hook, and said yoke is provided with a shoulder 32, with which engages one arm 33 of a three-armed lever that is pivoted on a stud 34, all of these parts being arranged within the switch-box of the telephone. A second arm 15 of this lever is the switch-arm, which may be moved to engage with the contact 14 to establish the local talking and signaling circuits, and, as before stated, these circuits are normally closed. The third arm 35 of this lever is yieldingly held in the position shown in Fig. 1 by means of a spring 36, this movement being limited in one direction by a stop-pin 37, and when 35 the arm 35 is operated upon by the selecting mechanism the other two arms will be moved—one to release the shoulder 32 and the other to engage with contact 14—and complete the load-circuits of the telephone.

40 At each station are arranged bearings for a spindle or arbor 40, that is provided at one end with a pointer 41, extending through the wall of the casing and arranged to travel over a dial 42, bearing numerals or other designating characters of a number equal to the number of stations on the party-line, the dial being preferably protected by a transparent panel. At a point within the casing the arbor carries two arms 43 and 43', and while all 45 of the pointers, dials, and arms 43' are the same and all stand in the same position when the line is not in use the arms 43 will be arranged in different angular positions at each station. These arms 43 are adapted to engage the arms 35 when the mechanism is operated, and thus effect the unlocking of the receiver-hooks and the closing of the local circuits. The arbor also carries a ratchet-wheel 45, having teeth of a number equal to 50 the number of numerals or other characters on the dial, and with said ratchet-wheel engages a pawl 46, that is carried at one end of an armature 47, arranged within the field of

force of the electromagnet 17, so that when the latter is energized the armature will be 65 attracted and will effect movement of the ratchet-wheel and arbor for an angular distance, depending on the number of times the circuit is made and broken. To prevent backward movement of the ratchet-wheel, a 70 locking-pawl 48 is employed.

The contact 18, previously referred to, is stationary, while the contact 19 is in the form of an arm carried by a rock-shaft 50, extending through the casing and provided at a 75 point outside the latter with a handled crank 51. Around the shaft 50 is coiled a small spring 52, that tends normally to keep the two contacts engaged. The upper end of the contact-arm 19 is extended within a small recess formed at the lower portion of the locking-yoke 31, and when the latter is in the position shown in Fig. 2 it is impossible to move the contact-arm out of position to break the circuit, this being accomplished only when the 85 yoke swings on its pivot as the receiver-hook rises.

Pivoted to the upper portion of the contact-arm 19 is a catch 54, having in its lower face a recess 55, which may be adjusted to a 90 position over a stationary pin 56 when the contact-arm is moved out to break the circuit, and when so engaged the arm will be held outward against the stress of the spring 52, and when the circuit is thus broken no 95 person along the line can operate the selecting mechanism. From the upper portion of the catch projects a cam 58, with which may engage a pin 59, carried by the locking-yoke 31, the parts being so arranged that when the 100 yoke swings on its pin 30 the pin 59 will engage the rounded cam 58 and move the catch to release position, thus permitting the spring 52 to again restore the contact 19 to circuit-closing position.

Tracing now the circuits, it will be seen that if at each local station the arm 43' is in engagement with the arm 35 and arm 15 is closing the circuits by engagement with the contact 14, arm 33 will be raised above the 105 shoulder 32, and the yoke 31 will be unlocked, although retained in its lowered position by the weight of the receiver on the receiver-hook. Contacts 18 and 19 are closed, and the switch 23 is in engagement with contact 110 25, thus closing the selecting-line, while the battery B is cut out.

If any subscriber wishes to communicate with another, he removes his receiver from the hook, and this results in upward movement of the yoke 31, the latter thus passing beyond the control of the locking-arm 33 at that station, and the yoke engages under the arm 33 and holds the latter in its adjusted position, so that the arm 15 is still retained 115 in a position to engage contact 14. The sub-

scriber then grasps the operating-handle 60, which is connected to the switch 23 and moves the latter to engage contact 22, thus connecting the battery in the line 16. This immediately energizes all of the electromagnets 17, and the latter will attract armatures 47 and pawls 46 will be moved, rotating the ratchet-wheels to the extent of a single tooth. This one movement is sufficient to move all 10 of the arms 43' from engagement with the arms 35 at all of the stations along the line, and the arms 33 at all of said stations will fall against the shoulders 32, locking the receiver-hooks at said stations and positively 15 preventing any upward movement of the receiver-hook switch. At the same time the arms 15 are moved to disengage the contacts 14, and the calling and talking circuit of every telephone, except that of the calling 20 subscriber, is broken. The position of the parts at this time is shown in Fig. 2. The subscriber then moves the switch 23 back to contact 25 and then again to contact 22 for a second energizing of the line, the operation 25 being repeated a number of times, depending on the number of the station to be called, and if this station is No. 6 the circuit will be completed six times and each of the electromagnets will be energized six times and will rotate the ratchet-wheels and arbors, causing 30 corresponding movement of all of the arms 43; but at the completion of the operation only that arm corresponding to station No. 6 will rest against the arm 35 and at that station only will the arm 15 be moved to engage 35 contact 14 and the arm 33 be moved to unlock the yoke 31, as shown in Fig. 3. It may here be mentioned that if any subscriber should remove his receiver from the hook 40 during this calling operation the shoulder 32 may bind against the end of the arm 33. The yieldable spring 36 then permits the arm 35 to move inward and allow the free passage of the arm 43, so that the mechanism will not 45 be stopped. At the completion of the selecting movement the calling and the called stations are the only two that are connected to the line, and the calling subscriber may then turn the magneto M and ring up the called 50 station; but the bells at the other stations will not be sounded. The subscriber at the called station then removes his receiver from the hook, and the talking-circuits are connected, the battery B being employed for the 55 primary of the inductorium, as usual, and in this connection it is to be observed that the customary battery may be employed as a source of energy for the selecting means, inasmuch as its use for this purpose will not interfere with its employment for telephonic 60 communication. After communication has been established either of the connected subscribers may turn the handled crank 51 and

by revolving the shaft 50 move the contact 19 away from the contact 18, thus wholly 65 breaking the selecting-line and preventing any other person from energizing the same. When so moved, the catch 54 will engage the pin 55 and the parts will be locked with the circuit broken until the receiver is again 70 placed on the hook, whereupon the pin 59 in descending engages the cam 58 and releases the catch, allowing spring 52 to again press the arm 19 into engagement with contact 18 and complete the circuit of the selecting-line. 75 After the conversation is finished the operating-handle 60 is moved to make and break the circuit again until the hands or pointers 41 at all of the stations are again restored to zero position, at which time the line will be 80 again opened for use by any other person.

In Fig. 7 is illustrated a slightly-modified construction of ratchet-operated member for controlling the locking and unlocking movements of the receiver-hook, this in the present instance comprising a disk having projections 43^a and 43^b for engagement with the arm 35 and a counterbalance or poise 43^c being employed at the opposite side of the disk. 85

Having thus described the invention, what 90 is claimed is—

1. In telephone system, a plurality of substations connected on a party-line, a receiver-hook at each station, a receiver-hook-locking member provided with a projecting shoulder, 95 a pivotally-mounted lever having one arm movable into engagement with the shoulder, the second arm of said lever having a give-way connection, and a selector arranged to engage the second arm of the lever. 100
2. In telephone systems, a plurality of substations connected on a party-line, a receiver-hook arranged at each station, a receiver-hook-locking member provided with a projecting shoulder, a pivotally-mounted lever 105 having one arm engaging the shoulder and a second yieldably-mounted arm having a give-way connection, and a step-by-step selector having a member arranged to engage the yieldably-mounted arm to effect release of 110 the receiver-hook when the latter is depressed by the weight of the receiver. 115
3. In telephone selecting mechanism, a receiver-hook-engaging member, means for locking the same in position, a selecting mechanism controlling the movement of the locking means, a selecting-line to which all of the selecting mechanisms are connected in series, and a switch for opening and closing the line, said switch being under the control of 120 the receiver-hook-engaging member. 125
4. In a telephone system, an electromagnetic selecting means at each station, a selector-line to which all of the mechanisms are connected in series, a switch arranged in the line, a spring tending normally to hold

the same in closed position, a catch carried by the switch, means with which said catch may engage to retain the switch in open position, a cam carried by the catch, and means under the control of the selecting mechanism and the receiver-hook for preventing movement of the switch while the receiver is on the hook, and for releasing the catch when the receiver is replaced on the hook.

In testimony that we claim the foregoing as our own we have hereto affixed our signatures in the presence of two witnesses.

RUBEN C. M. HASTINGS.
THURSTON MATHENY.
